UNITED STATES PATENT OFFICE.

ANDREW SANANDER, OF SPRINGFIELD, OHIO, ASSIGNOR TO THE FOOS GAS ENGINE COMPANY, OF SPRINGFIELD, OHIO, A CORPORATION OF OHIO.

GOVERNOR FOR EXPLOSIVE-ENGINES.

SPECIFICATION forming part of Letters Patent No. 760,762, dated May 24, 1904.

Application filed May 31, 1902. Serial No. 109,666. (No model.)

To all whom it may concern:

Be it known that I, ANDREW SANANDER, a citizen of the United States, residing at Springfield, in the county of Clark and State of Ohio, have invented certain new and useful Improvements in Governors for Explosive-Engines, of which the following is a specification.

My invention relates to improvements in explosive-engines; and the object of my invention is to provide means to automatically regulate and govern the supply of explosive mixture.

My invention consists of the constructions and combinations of parts hereinafter described, and set forth in the claims.

In the accompanying drawings, Figure 1 is an explosive-engine embodying my device. Fig. 2 is a longitudinal section of the regulating-valve, showing the tension device in elevation. Fig. 3 is a detail of the tension device. Fig. 4 is a detail of the valve stem or shaft with lever to governor, and Fig. 5 is a transverse section of the regulating-valve.

Like parts are represented by similar letters of reference in the several views.

In Fig. 1 I have shown my invention employed in an explosive-engine having the bed *a*, the cylinder *a'*, and the governor *a''*, driven by spur-gears from the crank-shaft, as shown. In constructing my regulating-valve I preferably provide the casing *b*, having an air-supply inlet *b'*, opening into a chamber *b''*, and a gas or gasoline supply inlet *b'''*, which I have shown with an inlet-valve *b''''*, opening into a chamber *b''''* in said casing, said chambers being formed by the central circular web or partition wall *b''''* and the laterally-extending partitions *b'''''*, joined to the outer wall of said casing. Said circular web or partition I provide with ports *b''''''*, preferably of the form shown, and within this circular partition I provide a hollow rotatable valve *c*, having ports *c'* equal in number and preferably of corresponding shape to the ports of said central web or partition, so as to register with same, and by rotating said valve the supply of explosive mixture is regulated. For the purpose of automatically governing this valve I

provide it with a stem or shaft *c''*, to which I attach a dog *c'''*, having a projection *c''''*, adapted to engage with one end of a lever *c'''''*, pivoted at *c''''* to the governor-frame, the other end of said lever being preferably provided with a roller *c''''''* to contact and be moved in one direction by the movable part *c''''''* of said governor. This movement is against the tension of the spring *c''''''*, which is attached at one end to the projection *b''''* of the casing and at the other end to the projection *c''''''* of the dog *c''''''*, which is also attached to said valve stem or shaft. On the casing I provide the stops *b''''''*, between which the projecting finger *c''''''* is interposed, sufficient play being given said finger to allow the opening and closing of the valve, and the finger *c''''''* will note on the scale *b''''''* the position of the valve. The lever *c'''''* being in contact with the projection of the dog *c''''''* and the tension-spring *c''''''* being adjusted to give the engine its normal speed the movement of the movable part of the governor against the tension of the spring will turn the regulating-valve and automatically regulate the supply, so as to keep the speed of the engine normal under varying loads.

I preferably provide the valve-shaft with antifriction-bearings and have shown the valve and its casing so formed as to carry the inner end of the shaft on balls *c''''''*, and the outer end is carried by the ball-bearing *c''''''*, secured to the bed by the bracket *c''''''*, and I further provide the spring *c''''''*, which bears against the dog *c''''''* and the cup of the bearing *c''''''* to hold said bearings in position.

The chambers *b''''* and *b''''''* I form of such relative size and number of ports as will give the best proportion to the explosive mixture. In the drawings I have shown two gas or gasoline supply ports and six air-supply ports; but the relative size of the chambers and the number of ports in each may be made as desired.

Having thus described my invention, I claim—

1. The combination with a hollow cylinder-valve the interior of which forms a mixing-

chamber having its outlet at one end and with inlet-ports in the side walls thereof, of a casting for said cylinder having an annular chamber therein extending around said cylinder 5 with ports through its inner wall adapted to register with the ports in said cylinder, partitions in said casing-chamber extending parallel with the axes of said cylinder dividing said chamber into two compartments for air 10 and fuel supply respectively, a tension device secured to said cylinder, a movable member of a governor, and means engaging said member and cylinder whereby the movement of said movable member will rotate said cylinder 15 against the tension of said tension device.

2. The combination with a hollow cylinder-valve the interior of which forms a mixing-chamber having its outlet at one end and with inlet-ports in the side walls thereof, of a casting 20 for said cylinder having an annular chamber therein extending around said cylinder, partitions in said casing-chamber extending parallel with the axis of said cylinder dividing said chamber into two compartments for the air and fuel supply respectively, ports in 25 said casing leading from each of said compartments and adapted to register with the ports in said cylinder, the combined area of the ports from one compartment bearing a 30 fixed relation to those of the other and means

to rotate said cylinder-valve to govern the supply and maintain the relative proportion of the explosive mixture.

3. The combination with a casing having a central longitudinal bore open at one end and 35 an annular chamber therein surrounding said bore with partitions extending parallel with the center line of said bore, dividing said chamber into two compartments for air and gas respectively, each having ports to said bore, of a hollow cylinder-valve adapted to fit in said bore, the interior of which forms a mixing-chamber having an outlet at one end and inlet-ports in its side walls adapted to register with the ports in said casing, a shaft 40 45 on which said valve is fixed, a tension device connected to said shaft, a projection on said shaft, a movable member of a governor, a pivoted lever the respective ends of which engage said member and projection to rotate 50 said valve against the tension of said tension device by the movement of said member, substantially as specified.

In testimony whereof I have hereunto set my hand this 26th day of May, A. D. 1902. 55

ANDREW SANANDER.
